UNITED STATES PATENT OFFICE

ED J. HOLLY, OF TAYLOR, TEXAS

AUTOMATIC RAILROAD GATE

Application filed June 30, 1928. Serial No. 289,470.

This invention relates to automatic means for closing crossing gates of railroads, the general object of the invention being to provide fluid pressure means for closing the gates which are actuated by an electric circuit closed by a train approaching the crossing, with valve means operated by the circuit for permitting the pressure to be released after the train passes the crossing so that the gates will open under the action of gravity after the train passes the crossing.

Another object of the invention is to provide means on the train whereby the engineer of the train can break the circuit to prevent the gates closing or to open them after they have been closed.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a plan view of a railroad crossing showing the gates in closed position.

Figure 2 is an elevation showing the gates closed in full lines and open in dotted lines.

Figure 3 is a sectional view showing the means for actuating the gates.

Figure 4 is a diagrammatic view of the circuits.

Figure 5 is a view showing the parts on the train for engaging the third rail for closing the circuits.

In these drawings, the gates 1 are pivoted to the supports 2 and are normally held in open position by the weights 3 in the usual manner. A casing 4 is arranged at the lower part of each support and a tank 5 is arranged below the casing of one gate, this tank containing oil or the like. A cylinder 6 is arranged in each casing and the piston 7 of each cylinder has its piston rod 8 passing through an opening in the top of the casing and has rack teeth 9 at its upper end for en-

gaging a gear 10 on the pivot of the shaft so that when the piston is raised, the rack engaging the gear will lower the gate.

A pump 11 is arranged in one casing and has an inlet pipe 12 depending into the tank. The outlet of the pump is connected by a pipe 13 with the bottom of the cylinder in the casing, this pipe containing a check valve 14. A second pipe 15 connects the pipe 13 at a point adjacent the cylinder with the top of the tank and a valve 16 is arranged in the pipe 15, the valve being normally held in open position by the spring 17 on its stem. A pipe 18 connects the pipe 15, adjacent the point where it connects with the pipe 13, with the cylinder in the casing of the other gate. A motor 19 is arranged in the casing and is geared to the pump for driving the same.

A lever 20 is pivoted at one end to a suitable support in the casing and has its central portion engaging the upper end of the stem of valve 16 and the outer end of the lever is engaged by an armature 21 of a solenoid 22 supported in the casing. Stationary switch parts 23 and 24 are arranged in the casing and a movable stem 25, provided with the bridge pieces 26 and 27, is slidably arranged between the switch parts, the stem being connected to a lever 28 pivoted to a hanger 29 in the casing and having a set screw 30 at its free end which is adapted to be engaged by the upper end of the piston when the same is raised, to disengage the part 27 from the part 23 and engage the part 26 with the part 24.

A third rail, composed of wires 31, is attached to one of the rails of the track by the brackets 32, the wires being insulated from the brackets and the parts of the third rail on each side of the crossing are connected together by a wire 33 which passes under the roadway. A conductor 34 connects the third rail with one of the switch parts 24 and a branch conductor 35 connects the conductor 34 with one of the switch parts 23. A conductor 36 connects the other part 23 with the motor and a conductor 37 connects the other terminal of the motor with the conductor 38 which is connected with the solenoid, the ground wire of the solenoid being shown at 100

39. The conductor 38 is also connected with the other part 24.

A battery B is carried by the train and conductors 40 connect the battery with the wheels 41 carried by parts of the train and engaging the third rail. A switch S is arranged in one of the conductors 40 so that the engineer can break the circuit to the wheels whenever he desires. As shown, these wheels are carried by the arms 42 pivoted to parts of the train and provided with springs 43 which press the wheels upon the third rail. The pressure can be regulated by the set screws 44 attached to stationary parts and engaging portions of the arms. I prefer to place one of these wheels on the locomotive and another on the tender so that one wheel will engage a wire of the third rail when the other wheel is passing from one wire to another so that the train can pass over a switch, for instance, without breaking the circuit. The wires are kept stretched by the springs 44 which connect their ends with some of the brackets.

25 From the foregoing it will be seen that when a train approaches a crossing, the wheels 41 will strike the third rail and thus current will flow from the battery B on the train through the conductors 40 to the third rail and will then pass over the conductors 34 and 35, though the switch composed of the parts 23 and 27, through conductor 33 to the motor and from the motor the current will pass through conductors 37 and 38, through 30 the solenoid to ground. The ground wire 39 will be connected to one of the rails of the track. Thus the motor will actuate the pump and the core of the solenoid will depress the lever 20 and cause said lever to close 35 the valve 16. The pump will pump the oil through the pipe 13 into the cylinder 6 and some of this oil will pass through the pipe 18 to the cylinder of the other gate. The pistons will therefore be raised and thus the gates 40 will be lowered. As soon as the piston strikes the screw 30 of lever 28, the stem 25 and its switch parts will be lowered, thus closing the lower switch and then current 45 will pass from the battery through conductor 34, the lower switch, conductor 38, through the solenoid, the circuit of the motor being broken. The pump will then cease to operate, but the core of the solenoid will continue to hold the valve 16 closed. Thus oil 50 cannot escape from the cylinders and thus the gates will remain closed while the train is passing the crossing. After the train has 55 passed the crossing, the wheels 41 will pass off the third rail and then the circuit to the solenoid will be broken so that the spring 60 17 will open the valve 16 to permit oil to drain from the cylinders back into the tank, thus permitting the weights 3 to raise the gates. A spring 48 is provided for returning 65 the switch and the lever 28 to their normal

positions with the upper switch closed. If the engineer wishes to open the gates after they have been closed by a train approaching the crossing, he can open the switch S, which will break the circuit and thus the gates will open and by opening the switch before the train strikes the third rail, the gates will not be closed.

70 A hood 45 is arranged on each piston rod and extends over a tubular member 46 which covers the hole in the casing through which the piston rod passes so that rain or snow is prevented from entering the casing.

75 I prefer to form each gate as shown in Figure 2, with the hangers 47 which are formed of flexible material so that a vehicle will not be damaged by striking the gate itself.

80 It is thought from the foregoing description that the advantages and novel features of my invention will be readily apparent.

85 It is to be understood that I may make changes in the construction and in the combination and arrangement of the several parts, provided that such changes fall within the scope of the appended claim.

90 What I claim is:—

Means for closing railroad crossing gates comprising a cylinder associated with each gate, a piston in each cylinder, a piston rod having rack teeth thereon, a gear on the shaft of each gate meshing with the rack teeth, a tank containing fluid, a pump having its inlet connected with the tank, pipes connecting the outlet of the pump with the cylinders, a discharge pipe connected with the first mentioned pipes, a valve in the discharge pipe, a spring for normally holding the valve in open position, magnetic means for closing the valve, a motor for operating the pump, circuits for the pump and magnetic means, a double switch for controlling the circuits, said switch closing the circuits of the magnetic means and the motor when in raised position and closing the circuit of the magnetic means and breaking the circuit of the motor when in lowered position, means for lowering the switch by the piston when said piston is in raised position, a third rail adjacent the track in advance of the crossing, a source of electrical supply on the train, brushes on the train for engaging the third rail, conductors connecting the brushes with a source of supply, a switch controlling the flow of current through the conductors from the source, and means for connecting the third rail to the circuits of the magnetic means and motor.

100 In testimony whereof I affix my signature.
ED J. HOLLY.
